UNITED STATES PATENT OFFICE.

JULIUS H. OPPENHEIM, OF DALLAS, TEXAS, ASSIGNOR TO TEXAS-LOUISIANA PATENTS COMPANY, OF DALLAS, TEXAS, A CORPORATION OF DELAWARE.

CONTAINER BINDER.

Application filed August 17, 1926. Serial No. 129,810.

This invention relates to new and useful improvements in container binders.

The object of the invention is to provide means for reinforcing the corners and edges 5 of containers, as well as for enclosing the same within a metal frame, whereby the container may be secured together without the use of nails, screws, or other fasteners, and also whereby its corners and edges are 10 protected from rupture during transportation and the strength of the container greatly increased.

A particular object of the invention is to provide a metal binder of a simple nature, 15 which may be easily and economically applied to a container and securely fastened thereon without the aid of nails, screws or other fastening devices and which, when assembled, will form a substantially integral 20 enclosing frame giving to the container greatly increased rigidity and ruggedness as well as symmetry.

Another object of the invention is to provide a binder corner unit, which may be 25 formed from a single sheet of metal, thus reducing the cost of production as well as the number of operations required.

A still further object of the invention is to provide a binder comprising a plurality 30 of corner units and interposed connecting members having their ends locked in the corner units in a simple and efficient manner and co-acting with said corner units to form a reinforcing frame.

35 A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a perspective view of a binder constructed in accordance with my invention 45 and applied to a container,

Fig. 2 is a plan view of the blank from which the corner unit is formed,

Fig. 3 is a plan view of one of the corner units,

50 Fig. 4 is an isometrical view showing the inner sides of a corner of the binder,

Fig. 5 is a side view of one of the connecting members,

55 Fig. 6 is an enlarged longitudinal sectional view showing the fastening, and

Fig. 7 is an isometrical view of a modified form.

In the drawings the numeral 10 designates a corner unit or member including three right-angular arms 11, 12 and 13 respectively. Each arm receives one end of a connecting member 14, which is telescoped thereinto. The arms and connecting members are right-angular in cross-section, thus affording maximum strength.

60 One of the novel features is the construction of the corner unit. In Fig. 2 I have shown the blank sheet of metal A, from which the unit is formed. This blank has a T-shape, and the stem B for forming 70 the arm 13 is preferably made shorter than the other arms, because as is shown in Fig. 1, the arm 13 is used on the vertical edges of the container and is not subjected to the transverse strain ordinarily imposed on the 75 arms 11 and 12, therefore material can be saved by shortening the arm 13.

75 The blank is scored along marginal lines C to provide portions which may be bent inwardly upon the blank to provide overhanging flanges 15. To facilitate the bending of these flanges, the blank has slits D at the intersections of the stem 80 B and the body. The blank is scored longitudinally along the line E and is bent 85 on this line at right-angles. It is also provided with a transverse line F on which it is bent at right-angles. In order to bend the blank on the line F, it is provided with a slit 16 extending inwardly to the intersection of the lines E and F and when the blank is folded on the line F, the inner end 90 of the arm 12 will overlap the inner end of the arm 11, the flanges being cut out at 17 so that the arms may overlap as is shown 95 in Fig. 3. The overlapped portions of the arms are suitably brazed, welded or otherwise secured as an integral structure.

A corner unit thus formed may be quickly 100 and economically produced and is superior to a unit formed of more than one piece. The flanges are open sufficiently for the members 14 to telescope thereinto and the ends of these members are provided with points 18 to facilitate inserting the same 105 in the ends of the arms.

110 In producing the blank A, slots 19 are formed at its ends on opposite sides of the lines E and F. Tongues 20 are cut to extend into the slots and are bent so that

their ends will extend inwardly when the arms are formed and engage teeth or sumps 21 formed in the members 14 near their ends.

It will be seen that all of the parts may 5 be readily stamped from sheet metal and produced at low cost. I prefer to provide only a few teeth at each end of the members 14 and not to make the binder adjustable to different sizes of containers, but merely 10 to provide enough teeth to take up the slack when the connecting members are locked in the arms; however, I do not wish to be limited to such an arrangement and a greater number of teeth may be provided 15 if desired. The binders may be made to fit particular sizes of containers and usually they will be so constructed.

In Fig. 7 I have shown a modified form in which the arm 13 is free from the slots 19 20 and tongues 20. This permits the arms 13 to be disconnected from the vertical members 14, and thus the top of the container may be removed. This modified form is particularly useful for containers in which crackers, 25 cakes and other articles are shipped and sold from the container.

In using the binder, a unit 10 is provided for each corner of the container, and the connecting members 14 are disposed along 30 each edge of the container and inserted in the arms 11, 12 and 13, the parts being pressed together so that the tongues 20 engage in the teeth 21, thus locking the parts in position and forming a reinforcing frame 35 completely surrounding the container. When the binder is once locked on the container it can be removed only by first prying up the tongues 20 so as to release the connecting members 14. In applying the 40 binder to a container, four corner units and connecting members are first assembled as a rectangular frame, with the arms 13 extending upwardly. The container is then placed in this frame and the vertical members 45 14 are then inserted in the arms 13. The top frame is then made by assembling four units 10 and four members 14, and this is placed on top of the container with the upper ends of the vertical members telescoping 50 into the depending arms 13. Any slack may then be taken up by compressing the binder so as to further telescope the members 14 into the arms.

It is pointed out that the binder may be 55 used on most any kind of box or container, and the latter may be made of any suitable material such as wood, metal fibre, cardboard, etc. The container may be constructed of panel pieces without fastening 60 devices and securely held together and adequately protected by the binder. The reinforced container is almost indestructible and its strength is greatly increased, thus permitting rough handling and high stacking 65 without fear of collapsing. It is apparent

that by prying up the tongues 20, the binder may be removed and thus has a salvage and resale value.

Various changes in the size and shape of the different parts, as well as modifications 70 and alterations, may be made within the scope of the appended claims.

What I claim, is:

1. In a container binder, a plurality of 75 corner units each comprising oppositely directed arms, connecting members telescoping the arms of adjacent units, and means for automatically locking the ends of the members to the arms when the former telescopic the latter.

2. In a container binder, a plurality of 80 corner units each comprising oppositely directed arms having inturned marginal flanges and fastening elements, and connecting members having their ends telescoping 85 the arms and their edges engaging in the flanges thereof, the members having provision at their ends for receiving the fastening elements, whereby the members and arms are fastened together.

3. As a sub-combination in a container binder, a corner unit formed from a single sheet of metal being bent at right angles along lines at right angles to each other and slit to permit inner ends of the longitudinal 90 members to overlap at the intersection with the transverse member, marginal flanges formed along edges of the unit, and fastening tongues upset from the unit.

4. A shipping container binder embodying 100 two sets of corner brackets, each bracket of each set comprising transverse arms and a longitudinal arm, each arm being in the form of an angle member including rectangularly disposed flanges, each arm of each corner 105 bracket being disposed at right angles to the other arms of the same bracket, the flanges of each arm of each angle bracket having trough-shaped longitudinally extended overhanging wings, extension pieces joining the 110 corresponding transverse arms of the corner brackets of each set, and extension pieces joining the longitudinal arms of corresponding corner brackets of the respective sets, each extension piece comprising rectangularly 115 disposed flanges slidably engaged for adjustment with the wings of the arms wherewith each extension piece co-operates, and means for effecting a locking engagement between the arms and the extension 120 pieces when the latter are telescoped into the wings of the former.

5. A shipping container binder embodying 125 two sets of corner brackets, each bracket of each set comprising transverse arms and a longitudinal arm, each arm being in the form of an angle member including rectangularly disposed flanges, each arm of each corner bracket being disposed at right angles to the other arms of the same bracket, the flanges 130

of each arm of each angle bracket having trough-shaped longitudinally extended overhanging wings, extension pieces joining the corresponding transverse arms of the corner brackets of each set, and extension pieces joining the longitudinal arms of corresponding corner brackets of the respective sets, each extension piece comprising rectangularly disposed flanges slidably engaged for adjustment with the wings of the arms, wherewith each extension piece co-operates, and means for effecting a step by step adjustment between the extension pieces and the arms, in a direction longitudinally of the extension pieces and the arms, said means and the wings constituting the sole mechanism for holding the binder in place on a container.

6. A shipping container binder, constructed as set forth in claim 5, and further characterized by the fact that the means for effecting a step by step adjustment embodies

racks on the extension pieces, and resilient pawls on the arms, the pawls being releasably engaged with the racks.

25

7. Means for assembling and holding loose panels in box form, comprising a binder framing enveloping the assembled panel pieces and universally adjustable to adapt it to the size and shape of the container, and means carried by the individual members of the framing for inter-engaging and locking to prevent separation and resist twisting.

30

8. A box binder comprising a binder frame for enveloping the box and universally adjustable to adapt it to the size and shape of the container, and means carried by the individual members of the framing for inter-engaging and locking to prevent separation and resist twisting.

35

In testimony whereof I affix my signature.

JULIUS H. OPPENHEIM.
